CLAIM

The ornamental design for a collection and feeding bottle, substantially as shown and described.

DESCRIPTION

FIG. 1 is a top perspective view of a collection and feeding bottle according to another embodiment of the design.

FIG. 2 is a bottom perspective view of the collection and feeding bottle of FIG. 1.

FIG. 3 is a front view of the collection and feeding bottle of FIG. 1.

FIG. 4 is a rear view of the collection and feeding bottle of FIG. 1.

FIG. 5 is a first side view of the collection and feeding bottle of FIG. 1.

FIG. 6 is a second side view of the collection and feeding bottle of FIG. 1.

FIG. 7 is a first end view of the collection and feeding bottle of FIG. 1.

FIG. 8 is a second end view of the collection and feeding bottle of FIG. 1; and,

FIG. 9 is a cross-sectional view of the collection and feeding bottle taken along line 27-27 of FIG. 7.

Portions shown in broken lines are for illustrative purposes only and form no part of the claimed design.
